JOSEPH DE LIPKOWSKI, OF PARIS, FRANCE.

COMPRESSED-AIR BRAKE.

1,084,574.

Specification of Letters Patent.

Patented Jan. 13, 1914.

Application filed December 13, 1911. Serial No. 665,552.

To all whom it may concern:

Be it known that I, JOSEPH DE LIPKOWSKI, of 94 Boulevard Flandrin, Paris, France, engineer, have invented certain new and useful Improvements in Compressed-Air Brakes, of which the following is a full, clear, and exact description.

The present invention relates to improvements in compressed-air brakes which are controllable at application and at release, and in which there exists a direct and constant relation between the air pressure in the train-pipe or the like and the air-pressure in the brake cylinders (upon the pistons), both at application and at release and independently of the piston-stroke, that is to say, independently of the wear of the blocks.

These improvements relate both to the distributor and to the accelerator of this type of brake, and consist in the following:—(a) The distributor of this brake is constructed in such a manner that the lubricating oil carried along by the compressed air, instead of being deposited in the different parts of the distributor and hindering its operation, is stopped upon entering the distributor and collected in a special sump whence it can be removed from time to time. (b) One of the diaphragms mounted upon the distributor-piston is replaced by a cup-leather, which is more easily fitted and can be replaced without having to dismount the whole mechanism; (c) The two remaining diaphragms are fitted so as to be easily replaced also without having to dismount the whole apparatus; (d) The distributor piston-rod may be extended to carry a second cup leather; the action exerted by the air upon this latter counterbalances that exerted upon the first and renders the action of the brake more sensitive.

The complete brake for one vehicle comprises a brake cylinder of the ordinary type with a piston, an air vessel termed the brake reservoir, a special air distributor at present called the triple valve, and a small reservoir called the distributor reservoir. In the case of a quick acting brake, there is added an accelerator.

The essential part of the brake is the air distributor which regulates the action of the brake. The remainder of the apparatus consists of the cocks, the couplings and the system of pipes which are sufficiently simple to need no further description.

The object of the distributor is to maintain a strict and constant relation between the fall of pressure made in the train pipe by the driver and the air pressure admitted to the brake cylinder, and this independently of the size of the cylinder which varies with different brakes according to the stroke of the piston which in turn depends upon the amount of wear of the brake shoes. To obtain this result it is necessary to render the action of the distributor absolutely independent of the air pressure in the brake reservoir and to replace this pressure which continually varies according to the stroke of the piston of the brake cylinder, by a constant pressure derived from air stored in a small separate reservoir which is termed the distributor reservoir.

The following description has reference to the accompanying drawings in which:

Figure 1 is a longitudinal section of the apparatus. Fig. 2 is a section at right angles to Fig. 1 with the internal portions of the apparatus removed. Fig. 3 is a transverse section on the line 3—3 of Fig. 1. Fig. 4 is another transverse section on the line 4—4 of Fig. 2. Fig. 5 shows the detail of the slide valve. Figs. 6, 7, 8 and 9 show the various positions of the slide valve, and correspond respectively to the running position, preparatory and release, neutral or cut out position and braking position.

The working part of the distributor consists of a slide valve A operated by a piston rod B fixed to two diaphragms B' and B³ of different diameters, and furnished at its center with a cup leather B². These different parts divide the interior of the distributor into four parts.

The space C situated below the diaphragm B' is always in communication with the train-pipe by means of the passage c' c² and the chamber c³. The space D situated between the diaphragm B' and the cup-leather B² is always in communication with the small reservoir by means of the passage d. The space E situated between the cup-leather B² and the diaphragm B³ communicates with the brake cylinder by means of the passages e', e². The space F situated above the upper diaphragm B³ communicates with the atmosphere by means of the passage f. Lastly the air from the brake reservoir reaches the orifice g³ situated vertically in the seat of the slide valve, by means of the openings g' and g².

The air from the brake reservoir can enter the brake cylinder only by passing at the desired moment through the lateral passage a' in the slide valve; thus this air has no influence upon the working of the distributor.

The opening b^3 in the slide valve seat communicates with the atmosphere by way of the circular channel and the opening b^5 (Fig. 2).

10 The action of the distributor is as follows: When the train is in motion, the parts of the distributor occupy the positions shown in Figs. 1 and 6. The compressed-air from the train-pipe enters the space C below the 15 piston B, by means of the chamber c^3 , and passages c^2 , c' and maintains the piston in the raised position; the slide valve at its lower edge then uncovers the openings b^4 and the air from the pipe immediately fills 20 the space D above the diaphragm B' and enters through the passage d into the distributor reservoir (Fig. 2). At the same time this air enters the vertical orifice g^3 in the face of the slide valve, by means of 25 the opening b' situated in the upper part of the seat of the slide valve, and the lateral passage a' , in order to pass, by way of the passages g' and g^2 to the brake reservoir which becomes filled with compressed air 30 at normal pressure. Thus both the brake reservoir and the distributor reservoir are in direct communication with the train pipe, while the brake cylinder communicates with the exhaust by means of the central recess 35 a^2 in the slide valve, and the passages e^2 and e^3 (Figs. 1, 2 and 5); the brake is thus kept released and the air reservoirs are supplied from the train pipe.

To produce an application of the brake 40 in a controllable manner the piston successively occupies three positions, (a) preparatory position, (b) neutral or cut-out position (c) braking position. These three periods succeed each other as rapidly as the 45 two periods of the Westinghouse valve and correspond to the following functions: (a) when the fall of pressure made by the driver 50 has reached a given point, the balance of the piston B is destroyed and it descends with the slide valve to the position shown in Fig. 7. The brake and distributor reservoirs are then cut off from the train pipe and from one another, because the lower part of the slide valve has closed the orifice 55 b^4 from the train pipe while the lateral passage a' of the slide valve has left the channel b' of the seat of the slide valve. At the same time the brake cylinder is in constant communication with the exhaust by means 60 of the central passage a^2 of the slide valve. It will be seen later that this position corresponds to the gradual release of the brake.

(b) If the pressure in the train-pipe continues to fall the piston rod B descends farther until the slide valve reaches the posi-

tion shown in Fig. 8. The two reservoirs belonging to the brake and to the distributor, remain cut off from the train pipe and from each other, as in the preceding position, but the brake cylinder is then cut off from the exhaust, for the whole width of the slide valve completely covers the orifice b^2 which leads to the cylinder. This is the neutral or cut-off position which produces neither braking nor release.

(c) Upon a fresh fall of pressure in the train-pipe, the piston rod B of the distributor descends again and this time as far as the end of the stroke, that is to say until it is stopped by the edge of the lower cover. The slide valve is then in the position shown in Fig. 9.

The two reservoirs, brake and distributor, still remain cut off from the train-pipe and from each other, but the brake cylinder is put into communication with the brake reservoir by means of the lateral opening a' in the slide valve which registers with the mouth of the orifice b^2 leading to the cylinder. The compressed air from the brake reservoir then enters the cylinder, actuates the piston and the brake gear and applies the brake by pressure of the brake shoes on the vehicle wheels. But at the same time the compressed air admitted into the cylinder enters the space beneath the diaphragm B³ and produces an upward pressure which tends to raise the piston rod B. This will continue until the pressure is sufficient to raise the piston and slide-valve to the neutral position. Now the fall of pressure in the train-pipe, under the action of the air in the distributor reservoir, results in a downward pressure on the surface of the diaphragm B' while the air admitted to the space E acts upwardly on the surface of the diaphragm B³ and the surface of the cup-leather piston. These surface areas may be conveniently designated S' for diaphragm B'; S² for the cup leather piston B² and S³ for the diaphragm B³. It is then evident that the braking will automatically stop only when the pressure of air admitted to the cylinder is in the same proportion to the reduction in pressure in the train-pipe, as the surface S' is to (S³-S²). This relation is evidently equal to

$$\frac{S'}{S^3 - S^2}$$

thus it is constant and accurately determined in advance by the sizes given to the diaphragms. The brake is then perfectly controllable, because to every fall of pressure created in the train-pipe there corresponds an accurately determined pressure in the brake cylinder. Further the intensity of the braking will be absolutely the same for all the vehicles of the train, because the effort is rigorously proportional to the pres-

sure retained in the train-pipe, and is absolutely independent of the stroke of the brake *i. e.* of the amount of wear on the brake shoes, because the action of the distributor is produced by a small separate constant-pressure reservoir and in no way depends upon the air stored up in the brake reservoir where the pressure varies from one brake to another according to the varying capacity of the brake cylinder that is to say according to the amount of wear on the brake shoes.

To effect the gradual release of the brake, the driver forces a certain quantity of compressed air into the train-pipe. The distributor piston then leaves the neutral position and rises to the position of Fig. 7. In this position the slide valve places the cylinder in communication with the exhaust by way of the passage a^2 in the slide valve, all this time keeping the brake reservoir completely cut off. The air in the cylinder thus escapes gradually, and the braking effort diminishes. But at the same time the upward pressure of the cylinder-air upon the surface $S^3 - S^2$ of the upper diaphragm diminishes also, until the pressure is no longer able to maintain the piston rod B which descends and takes up the neutral shut-off position. Thus there will come a time, as in the case of braking (but in the inverse manner), when the fall of pressure made in the cylinder will be as many times greater than the increase in the train-pipe, as the surface S' is greater than $S^3 - S^2$. The relation is then

$$\frac{S'}{S^3 - S^2}$$

that is to say the same as that which governs the brake application. A fresh admission of compressed air to the train-pipe, will produce a fresh release but always rigorously proportional to the pressure in the train-pipe, and so on up to complete release, that is to say, until the brake is completely free. At this moment the distributor-piston will be completely raised and the slide valve resumes the running position.

In point of view of construction the distributor embodies the following features:

(1.) There is arranged on the stem of the piston extended beyond the basin C, a second cup leather B^4 of the same diameter as B^2 but turned in the opposite direction. This additional piston balances the action of the air on the upper piston and thus makes the apparatus very sensitive and facilitates the application of braking pressure.

(2.) The piston carries at its center, a cup leather instead of a diaphragm which arrangement considerably simplifies the construction of the distributor and allows of more easily fitting up the parts and replacing the leather without having to dismantle the whole of the apparatus. At the same

time the cup leather is stronger and wears away less than a diaphragm.

(3.) The two diaphragms are mounted on the malleable iron pistons fixed separately on the central stem, each by a single nut. This arrangement allows each piston to be separately raised in order to examine or replace one or other of the diaphragms, without dismounting the whole of the apparatus.

Claims:

1. A compressed air brake comprising an upper chamber and a lower chamber, and a passage between the same, a piston rod extending through said passage from one chamber to the other, a flexible diaphragm secured to said piston rod at each end within said chambers, and a cup-leather mounted on said rod in said passageway and forming a piston, a distributing slide valve mounted on the piston rod for controlling the operation of the braking mechanism, and means for subjecting said piston to unequal pressure on opposite faces thereof to operate said valve in combination with a well opening into the base of the lower chamber, and having an internal diameter corresponding to that of the passage between the upper and lower chambers, a downward extension of the piston rod entering said well, a cup leather on said extension forming a piston in said well for the purpose described, the well having an aperture below the piston to admit atmospheric pressure to the lower face of the latter.

2. A compressed air brake comprising an upper chamber and a lower chamber, and a passage between the same, a piston rod extending through said passage from one chamber to the other, a flexible diaphragm secured to said piston rod at each end within said chambers, and a cup-leather mounted on said rod in said passageway and forming a piston, a distributing slide valve mounted on the piston rod for controlling the operation of the braking mechanism, and means for subjecting said piston to unequal pressure on opposite faces thereof to operate said valve, together with an air inlet chamber, a baffle arranged therein in front of the air inlet port, an air passage behind said baffle leading to the distributing valve and a drainage passage leading to the lower diaphragm chamber, substantially as described.

3. A compressed air brake comprising an upper chamber and a lower chamber, and a passage between the same, a piston rod extending through said passage from one chamber to the other, a flexible diaphragm secured to said piston rod at each end within said chambers, and a cup-leather mounted on said rod in said passageway and forming a piston, a distributing slide valve mounted on the piston rod for controlling the operation of the braking mechanism, and means for subjecting said piston to unequal

- pressure on opposite faces thereof to operate said valve, together with an air inlet chamber, a baffle arranged therein in front of the air inlet port, an air passage behind 5 said baffle leading to the distributing valve and a drainage passage leading to the lower diaphragm chamber, together with means serving to protect the diaphragm in said chamber for the entrapped fluid.
- 10 4. A compressed air brake comprising an upper chamber and a lower chamber, and a passage between the same, a piston rod extending through said passage from one chamber to the other, a flexible diaphragm 15 secured to said piston rod at each end within said chambers, and a cup-leather mounted on said rod in said passageway and forming a piston, a well opening in the base of the lower chamber, a downward extension of 20 the piston rod entering said well, a cup leather mounted on said extension and forming a supplemental piston in said well, said well being apertured in its lower portion to admit atmospheric pressure to the lower 25 face of said piston, a distributing slide valve mounted on the piston rod for controlling

the operation of the braking mechanism and means for subjecting said piston situated between the diaphragms to unequal pressure on the opposite sides thereof to operate said 31 valve.

5. In a compressed air brake of the character described, a piston rod threaded at its opposite ends, a slide valve mounted thereon intermediate its ends and moving with said 35 rod, a piston adjacent said valve on said rod, flexible diaphragms one above and one below said slide valve and piston, carriers for said diaphragms sleeved upon the rods, a second piston of like diameter below the lower dia- 40 phragm, and securing nuts threaded on the opposite ends of said rod to hold the parts in rigid relative position thereon, substantially as described.

In testimony whereof I have signed my 45 name to this specification, in the presence of two subscribing witnesses.
